UNITED STATES PATENT OFFICE.

FRANK TRAVNICEK, ALSO KNOWN AS FRANK GRINESS, OF EAST ST. LOUIS, ILLINOIS.

REACTION VACUUM PROPELLER.

Application filed June 3, 1925. Serial No. 34,619.

This invention is an improvement on the vacuum propeller set forth in my application Serial No. 727,192, filed July 21, 1924.

The principle of the present invention is that of modifying the vacuum in the bucket-like blades of the propeller by discharging compressed air, exhaust gases from an internal combustion engine, or jetting a fluid under pressure into the base path of the buckets at such velocity as will displace the air which has been expelled from the buckets or blades and due to which air explosion the vacuum effect is produced by the rotation of the propeller.

The utilization of this principle results in the reaction of the compressed air or gases and the reaction of the turning effect of the propeller being in the same direction as that of the suction on the buckets, which results in a propelling action.

The shape of the buckets of the propeller may be varied according to requirements of the resistances of the element, air or water, in which the propeller is designed to operate.

The modification of the vacuum is under the control of valve mechanism which may be of any kind adapted to serve the purpose. While I have illustrated rotary valves for this purpose, it will be obvious that poppet valves, or other valve gear, operated by a suitable cam shaft could be substituted for the gear operation of rotary valves which is illustrated and described. Similarly, while the buckets are shown as being of box-like form, they may be of cone shape.

The invention, as illustrated, is more particularly adapted for use for the propulsion of boats or ships in water but the blades or buckets may be constructed and arranged to adapt the propeller for use on aeroplanes, hydroplanes, and other flying machines.

The valve mechanism is timed so that the vacuum is produced, in a two-bucket, small diameter, rapidly revolving propeller, during three-quarters of a revolution for a given bucket and modified or destroyed for the remaining one-quarter revolution of said buckets so that the buckets will produce the highest vacuum when at the same point of their revolution and, on the other hand, the remaining bucket will have its vacuum modified or destroyed always when traveling through a certain part of its revolution.

For a propeller of larger size, the steam or

gas will issue, and the vacuum will be modified, during one-half of each revolution.

As explained in my aforesaid application, the vacuum effect is derived from the rotation of the propeller buckets or blades, the circumferential velocity causing the air to be expelled from the buckets to a lesser or greater extent according to the number of revolutions per minute, the higher the peripheral speed per second, the higher the percentage of vacuum created. As the vacuum will exist in both of the buckets, it becomes necessary to modify or destroy the vacuum in one bucket so that the reaction of the turning effect and the vacuum suction will be in the same direction.

This is accomplished, as previously set forth, by admitting compressed air or exhaust gases into the base path of the buckets, under timed control by valve mechanism.

My invention is not restricted to the employment of a pair of buckets as more than two buckets may be employed.

The embodiments of the invention which are hereinafter described and shown in the accompanying drawings are illustrative of the invention but are not in limitation of the scope thereof.

In the accompanying drawings:

Figure 1 is a plan view, parts being in section, illustrating one embodiment of the invention.

Fig. 2 is a front elevation.

Fig. 3 is a front elevation of a modification, parts being broken away;

Fig. 4 is an end view thereof, certain parts being broken away;

Fig. 5 is a plan view of a propeller having buckets of modified form;

Fig. 6 is a section on the line 6—6, Fig. 5, and

Fig. 7 is a section on line 7—7, Fig. 5.

Referring first to Figures 1 to 4 inclusive, the buckets or propeller blades 1 are of the vacuum type, being of the general construction disclosed in my aforesaid application except that they are not open on one side. They may be "canted", that is set angularly in relation to each other, if desired, but need not be thus disposed. The buckets are of wedge-shape, having their top and bottom walls 2, 3, meeting at a thin cutting edge 4. The walls 2 and 3 need not be dished as in my aforesaid application although they may be dished if preferred. The side walls 5 are

curved, those of one blade or bucket curving the same as those of the other blade or bucket.

The buckets 1 may be mounted for rotation by a connecting member independent of the tubular member or pipe which supplies the compressed air, exhaust gases or other fluid under pressure to the buckets and, for the purpose of bracing and strengthening, it may be found advantageous to connect the buckets by additional means but I have only illustrated a suitably rigid tubular connection or pipe 6 which serves both as a mounting for the buckets and as a conduit for supplying the vacuum-destroying compressed air or other fluid medium to the buckets. The pipe or tubular connection 6 is provided with nozzles 7 which are arranged to direct the compressed air or other medium outwardly from the open ends of the buckets 1 into the base paths of said buckets for the purpose of modifying or destroying the vacuum.

My preferred method of controlling the discharge of compressed air or exhaust gases through the pipes 6 comprises rotary valves 8, 9, whose stems have gear wheels 10, 11, respectively meshing with a pinion 12 which is carried by a fixed support or bracket 13, the pinion itself being fast on said bracket so that it cannot turn. A controlling arrangement of the character set forth will cause opening and closing of the valves 8, 9, as the buckets 1 and the pipe 6, and valves revolve, because the gear wheels 10, 11, will be turned by rolling on the fixed pinion 12.

The rotary valves 8, 9, will be so arranged, and timed by the gears, that the compressed air or exhaust gases from an internal combustion engine entering through feed pipe 14 which communicates with pipe 6, will have access to the buckets 1 during one-quarter of a complete revolution of the given bucket and will be cut off from a given bucket during the remaining three-quarters of a complete revolution. Thus, throughout ninety degrees of the complete revolution of a bucket, the vacuum produced by the revolution of the bucket will be destroyed and during the remaining three-quarters of the revolution, the vacuum will be unbroken and that the highest vacuum will always occur at the same point of the revolution.

The pressure of the compressed air or gases must be such that it will overcome the air pressure and will displace the air from the buckets.

As previously set forth, while the buckets 1 are of the general construction disclosed in my aforesaid application, their tops are not cut out and consequently the vacuum resistance is entirely in the opposite direction to the driving effort or effect and the vacuum suction acts in a line square to the central axis.

The propeller which I have set forth is particularly adapted for use in the propulsion of boats and ships in water. To utilize the principle for a propeller of an aeroplane or other flying machine, the propeller is modified to effect the pressure or reaction in a radial direction.

In Figs. 3 and 4 I have illustrated an embodiment of the invention in a different form, while utilizing the principle thereof. In this embodiment the propeller operates somewhat on the principle of a reaction turbine although the steam issues from one bucket, while the other bucket is creating a vacuum, the resulting reaction, in each instance, being in the same direction. This embodiment is not well adapted for use in water but is adapted for use in air for any vehicle employing an air-propeller.

The propeller of said figures is shown conventionally mounted in suitable standards 15 and has a rotor 16 provided with buckets 17, 18, which are open at their ends 19 and gradually decrease in size to points where their inlets 20 are located. A pipe or conduit 21 communicates with the inlets 20 and is controlled by valves 22, 23, whose stems carry gears 24, 25, which mesh with a pinion 26. The pinion 26 is fast so that it cannot turn.

Steam, as well as compressed air, may be utilized as the controlling medium and it is admitted under suitable control at 27 from which it flows to the pipe 21. The valves 22, 23, control the flow of steam to the inlets 20 of the buckets 17 and 18 in the manner previously described.

The vacuum is created by virtue of the velocity of the buckets, which causes expansion of the air inside of them.

I have found that if the buckets are of conical shape, higher vacuum may be obtained than possible with a bucket of cylindrical, untapered shape.

The principle involved in the embodiments of Figs. 1 and 2 and that of Figs. 3 and 4 is the same. Only one side of the complete propeller is at work at a given time, the other side minimizing the resistance as much as possible. This is the reason for destroying or modifying the vacuum, as previously explained.

In the propeller of Figs. 5, 6 and 7 inclusive, the shank 28 carries buckets 29 which may be canted, or set angularly in relation to each other. The tops of the buckets 29 are open but their bottoms 30, which are somewhat curved, are closed. The sides 31 converge to a point or knife edge 32. The action is substantially the same as in the case of the buckets of my pending application, Serial No. 727,192.

I claim:

1. In a reaction vacuum propeller the combination of vacuum producing buckets, or blades, having open parts, means of mount-

ing said buckets for rotation, and means for alternately modifying the vacuum produced by said buckets in timed relation with the forward movement of an aeroplane or other vehicle when said propellers are rotating in a vertical plane parallel with the major axis of said aeroplane or other vehicle.

2. In a reaction vacuum propeller the combination of vacuum producing buckets, or blades, having open parts, means for alternately modifying the vacuum produced by said buckets in timed relation with the forward movement of an aeroplane or other vehicle when said propellers are rotating in a vertical plane parallel with the major axis of said aeroplane or other vehicle, means for mounting said buckets for rotation, and means for delivering a fluid, under pressure, to said buckets at predetermined, alternate intervals for the purpose of modifying the vacuum produced by said buckets.

3. In a reaction vacuum propeller the com-

bination of vacuum producing buckets, or blades, having open parts, means for alternately modifying the vacuum produced by 25 said buckets in timed relation with the forward movement of an aeroplane or other vehicle when said propellers are rotating in a vertical plane parallel with the major axis of said aeroplane or other vehicle, means for 30 mounting said buckets for rotation, means for delivering a fluid, under pressure, to said buckets at predetermined, alternate intervals for the purpose of modifying the vacuum produced by said buckets, conduits leading 35 from a centrally located source of supply to said buckets, said conduits being adapted to be alternately opened and closed by suitable valve mechanisms, and means for rotating said buckets at velocities sufficient to create 40 a vacuum.

In testimony whereof I affix my signature.

FRANK TRAVNICEK,

Also known as Frank Griness.
